UNITED STATES PATENT OFFICE.

SAMUEL J. SHAW, OF MARLBOROUGH, MASSACHUSETTS, ASSIGNOR TO HIMSELF, THOMAS COREY, AND WM. E. C. WORCESTER, OF SAME PLACE; SAID WORCESTER ASSIGNS TO SAID SHAW HIS RIGHT.

IMPROVED EYELETTED BRACE.

Specification forming part of Letters Patent No. **58,954**, dated October 16, 1866.

To all whom it may concern:

Be it known that I, SAMUEL J. SHAW, of Marlborough, in the county of Middlesex and State of Massachusetts, have invented a new and useful or Improved Eyeletted Brace or Stay for the Lacing-Holes of Shoes, Corsets, or various other articles; and I do hereby declare the same to be fully described in the following specification, and represented in the accompanying drawings, of which—

Figure 1 is a top view, Fig. 2 a side elevation, and Fig. 3 a longitudinal section, of it.

This invention consists of a plate or piece of metal, *a*, and two eyelets, *b b*, stamped or formed together from such plate, such eyelets extending from the brace at or near its two extremities, the same being as shown in the drawings. In fact the whole may be said to be two eyelets and a connecting-brace, struck or formed in connection from one sheet or plate of metal.

I am aware that a brace and two separate eyelets have been used at the lower part of the lacing-opening of a shoe, the eyelets being

passed through holes made in the brace. Therefore I do not claim such. Neither do I claim an eyelet stamped from a plate of metal. Nor do I claim a brace made with mere points or prongs extending from it, as such differs from my brace in having no holes through it and its fastenings. In my brace such holes are for the reception of the lacing, whereby the brace is better held in place in the shoe.

I have made a new article of manufacture specially adapted for lacing-openings, and whether to extend across or to be applied to either or both sides of one of such openings.

What I claim as my invention, and as a new article of manufacture, for purposes as set forth, is—

The eyelets and brace struck or stamped together or in connection from one piece of metal.

S. J. SHAW.
